UNITED STATES PATENT OFFICE.

JESSE S. PACKER, OF SALT LAKE CITY, UTAH.

SASH-LOCK.

No. 823,543.

Specification of Letters Patent.

Patented June 19, 1906.

Application filed May 20, 1905. Serial No. 261,328.

To all whom it may concern:

Be it known that I, JESSE S. PACKER, a citizen of the United States, residing at Salt Lake City, in the county of Salt Lake and State of Utah, have invented certain new and useful Improvements in Sash-Locks, of which the following is a specification.

My invention relates to sash-locks, and has for its objects to provide a lock adapted to hold the upper and lower sashes in a relative position and to lock them in said position to the window-frame.

It is a further object to provide a sash-lock that cannot be torn from the sash.

With these and other objects in view the present invention consists in the combination and arrangement of parts, as will be hereinafter more fully described, shown in the accompanying drawings, and particularly pointed out in the appended claim, it being understood that changes in the form, proportion, size, and minor details may be made within the scope of the claim without departing from the spirit or sacrificing any of the advantages of the invention.

In the drawings, Figure 1 is a top plan view of my improved lock. Fig. 2 is a view of part of an upper and lower sash, showing my device attached thereto. Fig. 3 is a top plan view of the same.

Referring to the drawings, in which like numerals indicate corresponding parts throughout the several views, 1 is a plate upon the upper face of which are formed bolt-casings 2 and 3 at right angles to each other. Bolts 4 and 5 are longitudinally movable in their respective casings and are adapted to be entirely incased thereby. Slots 6 and 7 are formed in the walls of casings 2 and 3 to permit headed pins 8 and 9 to be secured to said bolts for the purpose of moving them into and out of locking position. Slot 7 is provided at its inner end with a short slot 7^a at right angles thereto, into which the pin 9 may be moved to prevent bolt 5 from moving outward when the sash is being raised or lowered. Plate 1 is provided with downwardly-extending side and end portions 10, 11, and 12, which form part of the means for securing the lock to the lower sash 13, 10 being provided with a screw-hole, while 11 and 12 are provided with projections 14 and 15.

My device is secured to lower sash 13 by cutting away the side rail to permit 11 and 12 to fit flush therewith, the projections 14 and 15 being driven into said rail or fit into holes provided for them. Screws passing through holes in the plate 1 and downwardly-projecting portion 10 hold the lock in position. Thimbles 16 are provided in frame 17 and in the face of side rail 18 of the upper sash at suitable distances in the path of travel of bolts 5 and 6. Into these thimbles bolts 5 and 6 are adapted to be moved. The thimbles 16 are provided with flanges and are held in the recesses provided for them by friction.

It will be observed from the foregoing that by moving bolt 6 outward into one of the thimbles on side rail 18 of the upper sash that the upper and lower sash will be locked together and may be moved as one sash, and by moving bolt 5 outward into one of the thimbles on frame 17 both sashes will be locked to the frame.

The sash-lock of my invention is simple in construction, inexpensive to manufacture, and of highest efficiency and durability in use. It cannot be opened with a knife from the outside, and it is practically impossible to tear it from the sash by forcing the window.

Having thus described my invention, what I claim as novel, and desire to secure by Letters Patent, is—

In a window-sash lock, the integral casing comprising a horizontal plate, a downwardly-extending flange adapted to be secured to the side of the lower window-sash, downwardly-extending flanges which overhang the edge of the lower window-sash and rest in a recessed portion, dowel-pins carried by said last-named flanges and entering the body of the window-sash and bolt-casings formed upon the horizontal bolt, said casings lying at right angles to each other, in combination with bolts slidably disposed in said casings.

In testimony whereof I affix my signature in presence of two witnesses.

JESSE S. PACKER.
